UNITED STATES PATENT OFFICE.

THOMAS L. LEE, OF ROCHESTER, NEW YORK, ASSIGNOR TO NORTH EAST ELECTRIC COMPANY, OF ROCHESTER, NEW YORK, A CORPORATION OF NEW YORK.

DESIGN FOR A WINDOW OF AN INSTRUMENT-DIAL.

59,557.

Specification for Design.

Patented Nov. 1, 1921.

Application filed May 12, 1921. Serial No. 469,057. Term of patent 14 years.

To all whom it may concern:

Be it known that I, THOMAS L. LEE, a citizen of the United States, residing at Rochester, in the county of Monroe and State of New York, have invented a new, original, and ornamental Design for the Window of an Instrument-Dial of which the following is a specification.

In the accompanying drawings Figure 1 is

a front-elevation of a dial provided with a window in accordance with the design of the present invention; and Fig. 2 is a section on the line 2—2 in Fig. 1.

I claim:

The ornamental design for a window of an instrument dial, as shown.

THOMAS L. LEE.
